UNITED STATES PATENT OFFICE.

WILLIAM PATRICK DAY, OF CLEVELAND, OHIO.

RAIL-SUPPORTING STRUCTURE.

1,317,779.

Specification of Letters Patent.

Patented Oct. 7, 1919.

Application filed January 22, 1919. Serial No. 272,467.

To all whom it may concern:

Be it known that I, WILLIAM P. DAY, a citizen of the United States, residing at Cleveland, in the county of Cuyahoga and 5 State of Ohio, have invented certain new and useful Improvements in Rail-Supporting Structures, of which the following is a specification.

This invention relates to improvements 10 in rail supports, and particularly to that type of rail support embodying spaced members extending transversely of the rails and rail supporting plates or chairs extending longitudinally beneath the rails and secured 15 to the transversely extending members.

The general object of this invention is to provide a rail supporting structure of this type which may be very cheaply made, which will be strong and rigid and which will be 20 adapted for use either in open or closed track work.

A further object is to provide a structure 25 of this character in which the rail supporting plates are formed with upwardly and outwardly extending flanges, which flanges will abut against the concrete filling of the road bed, so as to keep the support from shifting or slipping upon the concrete.

A further object in this connection is to 30 provide a construction of this character wherein the concrete will readily flow beneath the plates thereby insuring a uniform bearing under the entire surface of each plate and whereby the concrete can be 35 tamped in the usual manner and the tamping will force the concrete beneath the upturned side flange of the plate.

A further object is to so form the plates 40 that they may be stamped up at one operation to provide the upwardly and laterally extending flanges, said flanges performing the triple function of strengthening the plate, securing a firm bearing for the plate upon the concrete bed, and preventing lateral movement of the plates and the supporting structure as a whole.

Other objects will appear in the course of the following description.

My improved rail support is illustrated 50 in the accompanying drawings, wherein:—

Figure 1 is a top plan view of a rail support constructed in accordance with my invention;

Fig. 2 is a side elevation of the rail support illustrated in Fig. 1; and

Fig. 3 is a section on the line 3—3 of Fig.

1 but showing the rail support as disposed upon its concrete bed.

Referring to these drawings, it will be seen that my supporting structure includes 60 a pair of channel irons 10. I prefer to use channel irons for this purpose as thereby the structure is interlocked with the concrete bed by the lower flanges of the channel irons which would not be the case were 65 angle irons used. These channel irons 10 are arranged with their horizontal flanges extending away from each other, as shown in Fig. 2, and mounted upon these channel irons, at opposite ends thereof, are the rail 70 supporting plates 11 which extend lengthwise of the track and are intended to extend each beneath one of the rails A of the track. Each plate 11 is of steel and may be from $\frac{5}{16}$ " to $\frac{1}{2}$ " thick. Each plate, 75 on each side edge, is formed with the upwardly and laterally extending flange 12.

To this end the plate is constructed in a peculiar manner, and of a peculiar form. The plate is gradually narrowed from points 80 adjacent its ends to its middle and, as a consequence, the flanges 12 gradually narrow from the middle toward the ends and these flanges, which are, broadly speaking, slightly crescent shaped, are upwardly bowed and 85 the upper edges of these flanges 12 will curve slightly upwardly and inwardly. These flanges may be formed by stamping or pressing the sheet metal of the plate and the peculiar character of these flanges is such as 90 to very greatly strengthen the plate and render it rigid. These flanges are disposed along their entire extent at the same angle. The flanges terminate short of the ends of the plate 10 to provide a transverse flat terminal portion 13 at each end of the plate, this terminal portion lying flat upon and being riveted, bolted or otherwise attached to the upper flanges of the channel irons. The plate is to be provided with rail engaging devices 14 which may be of any 95 suitable character and form no part of the present invention.

In Fig. 3, I have shown the rail supporting structure above described in position 105 upon a concrete bed 15. It will be seen that while the upper surface of the concrete 15 is, generally speaking, level with the plates 11, the concrete between the plates and at the ends of the plates and immediately opposite the flanges 12 is raised to a level 110 with the upper edges of these flanges and

curved to correspond with the curvature of these flanges so as to form transversely extending abutments against which the flanges bear. It is obvious, of course, that the concrete along the entire bed might be on a level, with the upper edges of the flanges but preferably the concrete is rounded off opposite the flanges so as to conform to the shape of the upper edges of the flanges.

With this construction, the flanges 12 act to reinforce the concrete and the concrete acts as an abutment for the flanges. The concrete readily flows or is readily tamped into position beneath the flanges and thus a solid bearing is secured under the entire surface of the plate. Inasmuch as the concrete is embanked, as it may be termed, against the longitudinally extending flanges 12, it is obvious that this embankment of the concrete will prevent any lateral shifting of the road bed under stress and inasmuch as the flanges are curved longitudinally, due to the reduction in width in the middle of each plate 11, it will be obvious that a longitudinal interlock is secured between the plates and the concrete which will prevent longitudinal shifting of the track structure.

It will be seen that the supporting structure is held to the concrete by the interlocking engagement between the channel irons 10 and the concrete. Thus the track structure is held against movement in any direction independent of the road bed. This form of track supporting structure is particularly designed for street railways, though not necessarily limited thereto. It has been tried in practice and under service conditions and has been found to possess great strength and rigidity with the minimum of weight.

In laying a track with a supporting structure of the character described, the rails are engaged with each other by the clamping members 14 and then the rails are supported at intervals on jacks or by other means and disposed at the proper grade, level, etc., and then the concrete road bed is tamped beneath the rails and the supporting plates 11 around the transverse

members 10 in the manner shown in Fig. 3. When the concrete or like material has set, then the jacks are removed and concrete is filled into the spaces previously occupied by the jacks. Other means than jacks may be used for supporting the rails and plates 11 while the concrete or other ballast is being tamped beneath and around the track structure, and thus, for instance, blocks may be disposed at intervals beneath the rails or beneath the cross braces and then concrete poured or tamped in place, the supporting blocks being left in place after the concrete hardens.

I claim:—

1. A rail supporting structure comprising transversely spaced connecting supporting irons, having laterally extending flanges, and a pair of flat rail supporting plates mounted upon said irons, said plates extending parallel to each other and transversely to the irons, each plate being gradually contracted in width toward its middle between the supporting irons, said contracted portion of each plate being formed to provide oppositely disposed, upwardly and outwardly extending flanges, the outer edges of the flanges being substantially parallel.

2. The combination with a concrete road bed, of a pair of transversely extending spaced channel irons having laterally extending flanges, and a pair of rail supporting plates mounted upon said angle irons, said plates being flat and resting at their ends on the angle irons and attached thereto, said plates extending parallel to each other and transversely to the channel irons and each plate being gradually contracted in width toward its middle and the contracted portion of each plate being formed with oppositely disposed upwardly and outwardly extending flanges, the flanges being longitudinally curved, said angle irons and plates being embedded in the concrete bed and the upper face of that portion of the concrete bed abutting against said flanges being on a level therewith.

In testimony whereof I affix my signature.

WILLIAM PATRICK DAY.
